UNITED STATES PATENT OFFICE.

LOUIS SPEVACK, OF BROOKLYN, NEW YORK.

DESIGN FOR A CANDLESTICK.

49,286.

Specification for Design. Patented June 27, 1916.

Application filed February 3, 1916. Serial No. 76,057. Term of patent 3½ years.

To all whom it may concern:

Be it known that I, LOUIS SPEVACK, a citizen of the United States, and residing at Brooklyn, in the county of Kings and State of New York, have invented a certain new, original, and ornamental Design for a Candlestick, of which the following is a specification, reference being had to the drawing forming a part thereof, wherein the candlestick is shown in elevation.

I claim:

The ornamental design for a candlestick, substantially as shown.

LOUIS SPEVACK.
